CLAIM

The ornamental design for a barcode reader, as shown and described.

DESCRIPTION

FIG. 1 is a perspective view of a barcode reader showing my new design;

FIG. 2 is a front elevational view thereof;

FIG. 3 is a side elevational view thereof, the opposite side being a mirror image;

FIG. 4 is a rear elevational view thereof;

FIG. 5 is a top plan view thereof; and,

FIG. 6 is a bottom plan view thereof.

1 Claim, 3 Drawing Sheets

FIG. 2

FIG. 1

FIG. 4

FIG. 3

FIG. 6

FIG. 5
